PICTURE FRAME

Gregorio Mauricio Austria, Oxnard, Calif.

Application March 25, 1954, Serial No. 29,692

Term of patent 14 years

(Cl. D29—20)

To all whom it may concern:

Be it known that I, Gregorio Mauricio Austria, a citizen of the United States of America and residing at Oxnard, in the county of Ventura, State of California, have invented a new, original, and ornamental Design for a Picture Frame, of which the following is a specification, reference being had to the accompanying drawing, forming part thereof, in which:

Fig. 1 is a front elevational view of a picture frame showing my new design; and

Fig. 2 is a sectional view thereof taken along the line 2—2 of Fig. 1.

I claim:
The ornamental design for a picture frame, substantially as shown.
